HERSCHEL G. PACK, OF SAN FRANCISCO, CALIFORNIA

ATTACHMENT FOR VACUUM TUBES

Application filed August 2, 1929. Serial No. 383,018.

The present invention relates to attachments for vacuum tubes such as employed in radio and other electrical apparatus, and having base contact prongs releasably engageable with contact members in a socket for connecting the elements of the tube in electric circuit.

The primary object of the invention is to provide a device for attachment to vacuum tubes whereby electrical connection may be made to the base prongs of the tube thru means other than those provided for by the radio or other electrical apparatus in which the tube is used.

15 A further object of the invention is to provide an attachment for vacuum tubes providing a simple and efficient means whereby electrical connection to the elements of the tube and the circuits connected thereto may be obtained without disturbing the permanent electrical connections of the apparatus.

20 A further object of the invention is to provide an attachment adapted to be removably associated with the base prongs of a vacuum tube in a manner whereby electrical energy applied to the tube may be tapped for external use.

25 A further object of the invention is to provide an attachment of this character which when applied to the base of a vacuum tube in electrical connection with the base prongs thereof will not elevate the tube above its supporting socket to an objectionable extent and thereby permitting use of the attachment upon tubes mounted in cabinets or in other apparatus having but little clearance above the tube.

30 Briefly, the invention resides in the provision of an attachment adapted to be slipped over the base prongs of a vacuum tube whereby additional plate, grid or filament voltages may be applied to the tube, changes or additions may be made to the circuits connected with the tube, and microphones, phonograph pick-ups and similar apparatus may be connected in the apparatus without disturbing the permanent electrical connections to the tube sockets.

35 Other objects and advantages of the in-

vention will be apparent during the course of the following detailed description, taken in connection with the accompanying drawing forming a part of this specification and in which drawing:

Figure 1 is a sectional view thru the attachment shown applied to a vacuum tube and showing the tube in position in a conventional type of socket having electrical connection with the base prongs of the tube.

Figure 2 is a perspective view showing the attachment applied to the base of a vacuum tube.

Figure 3 is a top plan view of the attachment.

Figure 4 is a bottom plan view of the attachment.

Figure 5 is an enlarged fragmentary plan view of one of the spring contacts.

Figure 6 is a top plan view of an attachment for use with vacuum tubes having five base prongs.

In the drawing, and wherein similar reference characters designate corresponding parts thruout the several views, the letter A designates a vacuum tube of conventional construction, B a socket for removably receiving the tube A, and C the connector attachment for removable connection with the lower end of the tube A.

The tube A includes the base 5 provided with the usual contact prongs 6 projecting from the bottom flat side of the base for insertion into the socket B.

The socket B which is of ordinary construction includes the insulating base 7 of substantially flat formation and provided about its axial center with openings 8 for receiving the prongs 6 of the tube A. Mounted in the insulating base 7 as by suitable screws 9 are the usual contact members 10 having spring fingers 11 at their inner ends for engagement by the lower ends of the tube prongs 6 when inserted thru the openings 8. The outer ends of the contact members 10 are provided with the soldering tips 12 whereby conductors may be permanently attached in electrical connection to the outer ends of the contact members. In the form of tube and socket shown, proper placing of the tube

in the socket is insured by forming certain of the contact prongs 6 of greater diameter than the remaining prongs and correspondingly forming the openings 8 so as to properly receive the contact prongs.

The connector attachment C includes a supporting member or ring 15 which is formed from a suitable insulating material such as a phenol condensation product and 10 the external configuration of the member may either be circular, square or any other suitable shape. The member 15 is preferably provided with a circular opening 16 of a diameter slightly greater than the external diameter of the tube base 5. The supporting member 15 supports a series of metallic contact strips 18 which may be formed of spring brass or phosphor bronze, and one of the strips is provided for each contact prong of 15 the tube with which the connector is adapted to be associated.

These contact strips 18 are of substantially Z formation including flat base portions 19 having upstanding portions 20 at their outer 20 ends from the upper ends of which are out-turned attaching portions 21 for contact with the under surface of the supporting member 15. The flat base portions 19 are all disposed in a like plane and extend in a radial 25 direction with respect to the circular opening 16. Adjacent the inner end of each flat base or contact portion 19 is provided a prong receiving opening 22 provided with radially extending slots 23 permitting slight yielding 30 of the metal about the opening for frictionally receiving the tube prongs 6.

The upper outturned attaching portions 21 of the contact strips are apertured to receive the sets of threaded bolts 24 which project 35 upwardly thru the shanks of head member 15 and have threaded thereon binding nuts 25. Above the nuts 25 are knurled nuts 26 threaded upon the bolts 24. These bolts 24, nuts 25 and 26 aside from connecting the 40 contact strips in insulated relation upon the supporting member 15 also form terminals for connecting conductors to the independent contact strips 18 at a location above the supporting member 15.

50 In attaching the device to the base of the tube A the tube is first removed from the socket and the connector slipped over the base 5 with the prongs 6 passing thru the openings 22 in the flat base portions of the 55 contact strips 18. The tube may then be inserted in the socket B and it will be observed that the tube will only be elevated for the thickness of the contact strips 18 which are now disposed between the tube base 5 and socket B in electrical contact with the base 60 prongs 6. By observing Figures 1 and 2 it will be seen that the Z formation of the contact strips elevates the terminals or binding posts 30 a substantial distance above the 65 socket B and out of possible electrical contact

with any metallic portions thereof. Thus it will be seen that a conductor connected to one of the binding posts 30 will have electrical contact with one of the tube prongs 6 thru its associated contact strip.

When the connector attachment is applied to the tube base and the tube inserted in the socket it will be seen that electrical connection to the elements of the tube and a circuit connected thereto may be readily and efficiently made thru attachment of conductors to the binding posts 30 and without disturbing the permanent electrical connection of conductors to the soldering strips 12 of the contact members 10.

80 In the commercial built radio receiving sets and in various other types of electrical apparatus employing vacuum tubes, very little clearance is provided above the tubes and with the type of attachment shown it 85 will be seen that the height of the tube above the base is increased only a small amount and thus permits use of the attachment without alteration to the apparatus.

85 From the foregoing it will be apparent 90 that a novel and improved construction for a device of this character has been provided which will have an unlimited number of uses for making electrical connection to the elements of the vacuum tubes in various types 95 of electrical apparatus without disturbing permanent electrical connection to the socket of the tube.

In Figure 6, the socket B' has been shown 100 with the supporting member or ring 15' provided with five of the contact members 18' each provided with an independent binding post 30'. This form of connector is primarily intended for use with a vacuum tube having five base prongs.

105 Changes in detail may be made to the form of invention herein shown and described, without departing from the spirit of the invention or the scope of the following claims.

I claim:

110 1. A tapping connector attachment for vacuum tubes comprising a supporting member having an opening therethru for receiving the base of the tube, independent contact strips extending below the supporting member and having inturned flat lower end portions for engaging flat upon the lower end of the tube base and apertured to receive therethru the contact prongs of the tube, and a binding post connecting the upper end of each contact strip to the supporting member.

115 2. A tapping connector attachment for vacuum tubes having contact prongs insertable into a flat top socket, comprising a supporting member having an opening therethru for receiving the base of the tube, a series 120 of independent contact strips having flat base portions arranged in a like plane for receiving the contact prongs of the tube therethru, 125 130

an upturned portion at the outer end of each base portion, and an outturned attaching portion at the upper end of each upturned portion, and combined attaching and binding posts connecting the outturned ends of the contact strips to the underside of the supporting member.

3. A tapping connector for vacuum tubes comprising a supporting member of insulating material and having an opening therethru for receiving the base of the tube, independent contact strips each including a flat base portion, an upturned outer end portion and an outturned apertured attaching portion at the upper end of each upturned portion, said flat base portions being arranged

in radial relation and in a like plane and having prong receiving openings adjacent their inner ends, an attaching bolt connecting the outturned upper end of each contact strip to the underside of the supporting member and having threaded shank portions projecting above the upper surface of the supporting member, a binding nut threaded on each bolt at the upper side of the supporting member, and a clamping nut threaded upon the upper end of each bolt for electrically connecting conductors to the contact strips for electrical connection with the contact prongs of the tube.
